Des. 212,700
Patented Nov. 12, 1968

212,700

TOY FLAT IRON OR SIMILAR ARTICLE

Emil Teleki, 125 E. 15th St., New York, N.Y. 10003

Filed Aug. 29, 1967, Ser. No. 8,420

Term of patent 14 years

(Cl. D34—15)

FIGURE 1 is a front perspective view of my toy flat iron or similar article embodying my new design.

FIG. 2 is a top plan view thereof.

FIG. 3 is a side elevational view thereof, and FIG. 4 is a rear elevational view thereof.

I claim:

The ornamental design for a toy flat iron or similar article, substantially as shown.
